UNITED STATES PATENT OFFICE.

GOTTFRID HILDING KINBERG, OF HAMBURG, GERMANY.

COIN-COUNTER.

1,122,606.

Specification of Letters Patent.

Patented Dec. 29, 1914.

Application filed April 16, 1913. Serial No. 761,474.

To all whom it may concern:

Be it known that I, GOTTFRID HILDING KINBERG, a subject of the King of Sweden, and resident of Hamburg, Germany, have 5 invented a new and useful Coin-Counter, of which the following is a specification.

The present invention relates to counting apparatus for coins, counters and the like and more particularly to devices by the aid 10 of which different amounts of coins are counted as well as the complete stock of coins can be ascertained, so that either the single amounts are counted and paid out from the apparatus in different height or 15 continuously.

This device distinguishes itself by simplicity and nevertheless also by perfect reliability. Besides it is provided with a peculiar device hereinafter more fully described. 20 In this device the coins are taken singly from a rotatable counting disk or the like which at the rim is provided with notches or apertures, that successively pass a tube or funnel which is open at its lower end and 25 contains the coins to be counted which by the said disk are moved one after the other to a discharge opening or outlet. Now in counting apparatus of this kind the outlet or discharge is not close to the coin feed, but is 30 arranged in such manner that between the feed and the discharge there are several apertures of the counting disk. By this means on the one hand a control over the last fed coin is possible, so that wrong coins 35 or empty apertures will be noticed and an exchange or filling up may take place, before the counting mechanism combined with the apparatus is operated incorrectly. On the other hand it is possible to make use of 40 a locking member pressing against the upper surfaces of one of the coins fed from the stock and lying in the apertures of the counting disk, which locking device therefore locks the disk at every incorrect counting 45 with reliability. When the counting commences the counting disk must have made a certain movement before the first coin is discharged by reason of the distance of the outlet opening from the supply. Since for 50 counting a certain amount of coins a certain part of a rotation or a certain number of rotations of the disk must take place, the desired amount will be curtailed for a number of coins corresponding with that part of 55 the rotation necessary for initiating the counting, so that only such a number of

coins would be discharged which is less than the desired number of such lying in the apertures of the disk between the feed and the outlet. Such a mistake in the counting, 60 which can only take place at the commencement of the operation will be avoided or rectified by the device forming the matter of the present invention.

In the drawings a counting apparatus provided with a device mentioned above is shown by way of example. The counting apparatus is only illustrated to such an extent as is necessary to understand the invention.

Figure 1 is a plan of the apparatus and Figs. 2 and 3 are sections showing the mechanisms in different position. Fig. 2^a shows the detail in elevation.

The counting disk *a* is rotatably mounted 75 on the fixed top plate *b* of the apparatus and is rotated by a horizontal shaft *c* to allow the apertures to pass in succession below a coin feeding funnel *d* open at its lower end to allow each aperture to be filled by a coin. 80 Below the disk opposite the feed or funnel *d*, there is a discharge pipe *e* in line of which there is an outlet in the plate *b*.

Above the counting disk *a* next to the outlet tube *e* there is a locking bar *f* suitably 85 guided in a bracket vertically so as to drop freely when not held in raised position. This locking bar bears on the coins lying in the apertures, but drops into the first empty aperture that presents itself and thus locks 90 the counting disk against rotation, whereby the amount of coins discharged through the apertures is counted by the counting mechanism operated or influenced by the counting disk or the shaft *c*.

To the shaft *c*, which on each revolution causes the rotation of the disk *a*, for one revolution, a collar is attached, carrying on one side a nose *g* and on the other side a lateral stud *h* projecting parallel to the shaft *c* 100 Figs. 2 and 3. Below this stud a toothed segment *k* is arranged pivotally on the fixed stud *i*, into the teeth of which segment the stud *h* will engage on each revolution of the shaft *c*, whereby the toothed segment *k* will 105 be rotated for one tooth. The segment is held against backward rotation by a pawl *l*, and is returned to its initial position by a weighted lever *k'*, when the pawl is released, for instance by a knob or key *m*.

The initial position of the toothed segment *k* is determined by a stop *n* Fig. 2,

against which an arm o of the segment k will bear, and which is arranged on an arm p in a manner hereinafter more particularly described, the arm p being pivoted to the 5 stud i of the segment. To the arm p an upright bar q is pivotally attached, the upper end of which bar projects out through the plate b and is here provided with a number of slits q' , which may engage the edge of 10 the plate b at the slot, through which the bar q projects, to lock the bar q or the stop n in different positions of height. The slits in the bar q are at equal distances apart, the distance or pitch being so chosen, that the 15 adjustment of the stop n corresponds with the length of one tooth or the length of a plurality of the teeth of the segment k .

The step by step oscillation of the segment k , for one tooth by the stud is limited by the 20 aid of a stop r , with which the nose g engages when the stop r on the oscillation of the toothed segment projects into the path of the nose g as may be clearly understood from the dotted lines shown in Fig. 3. By 25 determining the position of the bar q the toothed segment k can be so adjusted that the stop r will interrupt the operation when the shaft c and the counting disk a have rotated a predetermined number of revolutions. The collar carrying the nose g is so 30 arranged on the shaft c , that the nose engages the stop r at such moment, when with regard to the outlet tube e the last of the 35 revolutions of the counting disk to which the adjustment has been carried on, is finished.

If now the counting disk a is provided 40 with ten apertures as shown and is rotated so far, that the first of the coins lying in the apertures reaches the outlet on each further rotation of the counting disk, ten coins will be paid out, that is to say on four rotations forty coins, on five rotations fifty coins, on six rotations sixty coins and so on will be 45 paid out. It will therefore be clearly understood that by suitable adjustment of the toothed segment k a certain amount of coins will be paid out in any desired repetition and each amount can be taken out between 50 the locking and the release on the counting disk, while a new tube can be introduced at the outlet space to catch the next following amount of coins.

When it is desired to count a certain stock 55 of coins, the bar q is secured in its highest position, as shown in Fig. 2. Thus also the stop n is placed in its highest position and the toothed segment k may rotate to such extent, that, after the segment k has been 60 moved backward for one tooth by means herein after described, a tooth will be situated under the shaft c , which on account of its small height does not project into the path of the stud h , so that the shaft can be 65 rotated without being acted upon by the seg-

ment. In the position shown in Fig. 2 this adjustment has not yet taken place.

Since between the coin feed and the coin discharge there are several apertures (four), it will be understood that no coin will be discharged by the counting disk until the disk has executed half a revolution. When this half revolution is carried out the toothed segment k is moved on for one tooth because at the commencement of the counting, disk a is in such position, that even on the first half revolution of the counting disk the toothed segment will be moved on for one tooth. The movement for one tooth of the segment should however correspond to 80 one complete revolution of the counting disk. Should by way of example for a certain amount of money five complete revolutions be necessary, and should the toothed segment be so adjusted that it will prevent 85 rotation of the shaft c after five teeth have been moved on, then the counting disk would be only able to rotate for four revolutions, since the first half revolution of the counting disk (during which no coin is discharged) has already operated the segment for one tooth. Now in order to enable the wanting fifth revolution to take place the segment k is moved backward at the beginning of the operation a distance of one 90 tooth. This backward adjustment will be compensated by the first half rotation, so that for the following five complete rotations five teeth can be moved on before the counting disk is arrested on account of the 95 nose g hitting against the stop r . When these complete rotations of the counting disk take place the operation of the segment by the stud is carried out during the second half of each revolution and the positions 100 of the nose g with respect to the stud h is such, that it strikes against the stop r when the second half of the last rotation is finished.

It will be understood from the foregoing, 110 that at the commencement of the counting an additional movement of the segment takes place over and above that, which corresponds to the necessary number of revolutions of the disk, which additional movement will be carried on by hand and acts during the first half rotation of the counting disk. When a second or other following counting is carried on, the said backward movement does not take place, since the 115 apertures of the counting disk up to the outlet or discharge tube are always filled, and on every continued rotation coins are at once 120 discharged. The backward adjustment of the toothed segment k is accomplished by a 125 second stop s provided for on the oscillating arm p for determining the initial position of the toothed segment. This second stop s is situated higher than the first stop n to such an extent, as will correspond to the move- 130

- ment of the tooth explained above. To enable the toothed segment to bear against the stop *s*, as is shown in Fig. 3, the stop *n* is adapted to be released or adjusted on the 5 oscillating arm *p*. This is accomplished by reason of the stop *n* not being firmly attached to the arm *p*, but is attached to a bell crank lever *t*, which is rotatably fastened to the crank lever *t*, which is rotatably fastened to the arm *p* and which is acted upon by a 10 spring *t'* tending to press the lever *t* against a stop (for instance the stop *s*). The other arm of the bell crank lever *t* is pivotally connected with a rod *u*, which is slidably guided on the bar *q* and projects through 15 the plate *b* carrying at its upper end a knob *u'*, thus forming a key. By pressing this key down the stop *n* can be moved from the arm *o* allowing the latter to bear against the upper stop *s*.
- 20 At the commencement of the counting the key *m* for releasing the locking pawl *l* and the rod *u* are pressed downward simultaneously so that the toothed segment is set or moved on for one tooth. The first amount 25 once being counted only the key *m* will be pressed down for every following counting so that the arm *o* now will always strike against the stop *n*.
- I claim:
- 30 1. In an apparatus for counting coins and the like, a counting mechanism comprising a disk having a number of apertures, a toothed member adapted to move for one tooth on every revolution of the counting 35 disk, a stop to determine the initial position of the toothed member, a second stop to determine the end position of the toothed member when moved to a distance corresponding to the amount to be counted, and 40 a movable carrier for the first named stop, which carrier is suitably guided and adapted to be fixed in different positions.
2. In an apparatus for counting coins and the like, a counting mechanism comprising 45 a disk having a number of apertures, a toothed segment arranged to progress one
- tooth for every revolution of the counting disk, a stop to determine the end position of the segment when moved to a distance corresponding with the amount to be counted, 50 an arm pivoted to the axis of the oscillating segment and carrying the stop for determining the initial position of the segment, and a bar to operate said arm and arranged to be fixed in different positions. 55
3. In an apparatus for counting coins and the like, a counting mechanism comprising a disk having a number of apertures, a toothed segment arranged to oscillate one tooth on every revolution of the counting 60 disk, a stop to determine the end position of the segment when moved to a distance corresponding with the amount to be counted, an arm pivoted to the axis of the oscillating segment, a second stop fixed to said arm and 65 a third stop adjustably mounted on said arm, both of said stops determining the initial positions of the segment, the last named stop determining the initial position of the segment for its first movement. 70
4. In an apparatus for counting coins and the like, a counting mechanism comprising a disk having a number of apertures, a toothed segment arranged to oscillate one tooth on every revolution of said disk, a stop 75 to determine the end position of the segment when moved to a distance corresponding with the amount to be counted, an arm pivoted to the axis of the oscillating segment, a stop fixed to said arm and a third stop, a 80 bell crank lever carrying the said third stop and pivotally attached to said arm, said lever arranged to be manually operated to allow a backward movement of the segment preparatory to making its first movement 85 corresponding to the initial filling of the apertures.

GOTTFRID HILDING KINBERG.
